(57) **CLAIM**

The ornamental design for an electronic cigarette, as shown and described.

DESCRIPTION

FIG. 1 is a first perspective view of an electronic cigarette; FIG. 2 is a second perspective view of the electronic cigarette;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view shown in a state of use.

The broken lines in the drawings depict portions of the electronic cigarette that form no part of the claimed design.
